(57) **CLAIM**

The ornamental design for tire tread, as shown and
described.

DESCRIPTION

FIG. 1 is a front view of a tire tread, showing the new design,
a rear view thereof, a top plan view thereof, a bottom plan
view thereof appearing the same as the front view;

FIG. 2 is a right side view of the tire tread, a left side view
thereof appearing the same as the right side view;

FIG. 3 is a fragmentary front view of the tire tread, showing
in enlargement the portion of the line 3—3 and in the
direction of arrows in FIG. 1.

FIG. 4 is a cross-sectional enlarged view of the tire tread
taken along line 4—4 and in the direction of arrows in FIG.
3; and,

FIG. 5 is a perspective view of the tire tread.

In the drawing figures on the enclosed drawing sheets, in
which the even broken lines represent environmental struc-
ture only and form no part of the claimed design, the claimed
design being the tread pattern shown by solid lines, up to the
peripheral boundary between the tread and the sidewall of
the article, represented by dot-dash broken lines.

The dot-dash broken lines form no part of the claimed
design.
